L. S. BRACH

LIGHTNING ARRESTER

Filed May 17, 1919

Leon S. Brach, INVENTOR
Charles Hermon, ATTORNEY

UNITED STATES PATENT OFFICE.

LEON S. BRACH, OF EAST ORANGE, NEW JERSEY.

LIGHTNING ARRESTER.

Application filed May 17, 1919. Serial No. 297,745.

This invention relates to lightning arresters, particularly to arresters of the cartridge type, and one of the objects thereof is to provide new and improved means for connecting 5 an arrester of this type with the line terminals as well as with ground.

Another object of the invention is to provide a mounting for a cartridge form of arrester, wherein a great economy of space is 10 accomplished.

A further object of the invention is to provide a device which is compact, and is simple in construction, and which therefore can be manufactured at a modicum of cost.

15 Other objects and aims of the invention, more or less specific than those referred to above, will be in part obvious and in part pointed out in the course of the following description of the elements, combinations, arrangements of parts and applications of 20 principles, constituting the invention, and the scope of protection contemplated will be indicated in the appended claim.

In the accompanying drawings, wherein I 25 have illustrated preferred forms of embodiment of my invention:

Figure 1 is an elevational view of one embodiment of my invention.

Figure 2 is a top plan view of the embodiment illustrated in Figure 1.

Referring now to the drawings, wherein similar reference characters refer to similar parts throughout the several views thereof, the reference numeral 1 denotes the base portion 35 of the device, the same comprising a block of insulating material, such as porcelain, or the like. Extending upwardly from the base, and molded or otherwise fastened therein, are line terminals 2 and 3 respectively, one of said terminals being located at 40 each end of the base. Mounted upon raised portions 4 and 5 provided upon each end of the base member 1, is a plate 6, the terminals 2 and 3 extending through apertures formed 45 in this plate. Suitable clamp nuts 7 and 8 threaded upon the terminal members 2 and 3 serve to hold plate 6 firmly in position upon the base member, each terminal being provided with suitable nuts and washers indicated at 9, by means of which the line wires are attached thereto.

50 The plate 6, which is of course formed of

metal, midway of its length, is provided with an aperture adapted to receive the theraded terminal 10 of an arrester 11. In the present instance the type of arrester illustrated is similar to that disclosed in my co-pending application Serial Number 297,746. That is to say, it is a vacuum type of arrester wherein a spark gap is provided interiorly of an evacuated chamber between spaced electrodes, the terminal 10 being electrically connected with one electrode, and the terminal 12, at the upper end of the device, being connected with the other electrode.

65 The threading of the terminal 10 into the plate 6 mechanically, as well as electrically, connects the arrester with said plate and therefore connects the same with the line terminals 2 and 3.

70 Referring to Figures 1 and 2 above described, it will be noted that the terminals 2 and 3 may be connected in the line, and the terminal 12 with ground. It will also be obvious that this arrangement may be reversed and the line connected with the terminal 12 and either of the terminals 2 and 3 connected with ground.

75 Thus it will be seen that I have provided a construction well adapted to attain each and every of the objects and ends above enumerated, in an exceedingly simple yet efficient manner. The device is simple, compact, and the construction is such that the arresters may be easily and quickly detached from 80 their supporting bases. While I have shown the line plates as adapted for screw threaded terminals, it will be obvious that it lies within the scope of my invention to provide other attaching means to accommodate different forms of the cartridge type of arresters.

85 As many changes could be made in this construction without departing from the scope of the following claim, it is intended that all matter contained in the above description or shown in the accompanying drawing shall be interpreted as illustrative only and not in a limiting sense.

90 Having thus described my invention what I claim as new and desire to secure by Letters Patent is:

95 A device of the class described, comprising a base formed of a block of insulating ma-

terial, a terminal carried by each end of said base, a metallic plate connecting said terminals and fastened to each of them, said plate intermediate its ends being provided with a threaded aperture, and a lightning arrester having screw threaded terminals projecting from each end thereof, one of said

terminals being adapted to be threaded into the aperture of said plate, the other terminal on said lightning arrester being adapted to be connected with ground. 10

In testimony whereof I affix my signature.

LEON S. BRACH.
